UNITED STATES PATENT OFFICE.

ELMER R. THOMAS AND PEARLEY E. LANGFITT, OF SHIDLER, OKLAHOMA.

PUMP JACK.

Application filed December 4, 1924. Serial No. 753,938.

To all whom it may concern:

Be it known that we, ELMER R. THOMAS and PEARLEY E. LANGFITT, citizens of the United States, and residents of Shidler, in the county of Osage and State of Oklahoma, have invented certain new and useful Improvements in Pump Jacks, of which the following is a specification.

This invention relates to pump jacks for use with oil well equipment and aims to provide a simple, novel and effective means for transmitting motion from the shackle rod line to the polish rod and also to provide means for preventing injury or damage to the mechanism of the jack or to the associated parts of the oil well equipment in the event of breakage of the shackle rod line.

Other objects and advantages of the invention reside in certain novel features of the construction, combination and arrangement of parts which will be hereinafter more fully described and particularly pointed out in the appended claims, reference being had to the accompanying drawings forming part of this specification, and in which:

Figure 1 is a view in side elevation showing one embodiment of the invention.

Figure 2 is a fragmentary group view in perspective of certain of the parts prior to assembly, and

Figure 3 is a view in end elevation looking toward the left of Fig. 1.

In the drawings, a base is designated at 1 and on the base 1 spaced sills 2 are supported and secured. Standards 3 extend vertically from the base and have their lower ends suitably secured to the sills 2. Brace members 4 and 5 are provided for the standards 3, the brace members extending between the sills 2 and the standards 3 and being suitably fastened to both.

The upper ends of the standards 3 carry bearings 6 which receive trunnions 8 projecting from the sides of saddle 9 on which the centers of the spaced members 10 of a walking beam 11 are fastened.

At one end of the walking beam 11 a bearing block 12 is secured, the bearing block having a body portion 13 which fits between the members 10 and is secured thereto having flanges 14 continuous with its top and resting on the tops of the members 10. The forward end of the bearing block is slotted, as at 15, from its top to its bottom and portions of the bearing block on the opposite sides of the slot 15 are provided with aligned

grooves 16 to receive the trunnions 17 of a timber screw 18 or other suitable device, whereby the walking beam is connected to the polish rod 19.

For transmitting motion from the shackle rod line to the walking beam a truss frame, designated generally at 21, is provided and includes spaced horizontal members 22,

spaced vertical members 23 and an inclined member 24. The members of the truss frame are secured to each other and are held in spaced relation by virtue of the interposition of the reduced extensions 25 of the inclined member 24 in between the spaced elements of the horizontal and vertical members 22 and 23. A bearing block 26 is provided to facilitate connection between the truss frame and the shackle rod line and has a portion 27 extending between and secured to the elements of the vertical member of the truss frame and this also aids in holding the parts in spaced relation.

A bearing block 28 is secured to the elements of the horizontal member of the truss frame and has a portion 29 interposed between the elements of this horizontal member 22 and secured thereto.

The elements of the horizontal truss member will extend beyond the vertical member 23, as indicated at 30, and these extensions 30 are pivotally mounted, as at 31, on the upper end of a link 32 which is pivotally secured, as at 33, to a bearing block 34 fastened to the sills 2.

The position of the link 32 is controlled by means of a rod 35 which has a turnbuckle 36 embodied therein. The rod 35 connects to the stationary structure of the base or to the casing head.

The motion of the truss frame is transmitted to the walking beam by means of a pair of oppositely disposed U-shaped stirrups 40 having their legs secured to a connecting base 41. One of the stirrups engages the block 28 and the other engages a block 42 fastened to the spaced members of the walking beam.

In order to prevent damage or injury to the elements of the jack or to the associated elements of the oil well equipment in event of breakage of the shackle rod line a supporting post 50 is provided and is pivotally connected, as at 51, at its lower end to the ends of the sills 2 adjacent the polish rod. The upper end of this post is designed to engage the walking beam 11 when the end of the same which is connected with the

polish rod swings downwardly just below the position which it assumes at the lower limit of the downward stroke as when the shackle rod line has been broken. For the 5 purpose of properly positioning the post 50 a link 55 is provided and has one end pivotally connected to the post, as at 56, and has its other end pivotally connected to the vertical member 23 of the truss frame, as 10 indicated at 57.

With this arrangement, during the normal operation of the jack and so long as the shackle rod line remains intact, the supporting post 50 is not engaged with the walking beam since its upper end is immediately 15 below the lowest position assumed by the walking beam at such times.

In the event the shackle rod line breaks the weight of the polish rod and the parts 20 carried thereby tends to cause the polish rod to move forcibly down to an extent beyond the limit of its normal stroke and consequently break or injure the parts of the oil well equipment and the parts of the 25 pump jack. Such excessive downward movement is, however, prevented in the structure proposed by the present invention for as soon as the shackle rod line breaks the resulting movement of the pump jack 30 swings the post 50 to the right as viewed in the drawings to position the same to engage the walking beam and support the same and consequently the parts of the oil well equipment connected therewith.

35 We claim:

1. A pump jack including a walking beam and a shackle rod line and comprising means for transmitting motion from the shackle rod line to the walking beam, and 40 a supporting post operated from said means and engageable with the walking beam to support the same and the parts carried thereby in the event of breakage of the shackle line.

45 2. A pump jack including a walking beam and a shackle rod line and comprising motion transmission means between the shackle rod line and the walking beam, said motion

transmission means including a truss frame having a horizontal member pivotally supported on the base of the jack and connected with the walking beam and also having a vertical member connected with the shackle rod line, a supporting post engageable with the walking beam for supporting the same and the parts carried thereby in the event of breakage of the shackle rod line, and a link connecting the vertical member of the truss frame and the supporting post. 50 55

3. A pump jack including a base, a sill 60 on said base, a standard secured to the sill, a walking beam pivotally supported on the standard, a shackle rod line and motion transmission means between the shackle rod line and the walking beam and comprising a truss frame including a lower member and 65 a vertical member, a pivoted standard connected with the base and connected with one end of the lower member of the truss frame for supporting the same, means for connecting the vertical member of the truss frame with the shackle rod line, and a connecting rod between the lower member of the truss frame and the walking beam. 70

4. A pump jack including a walking 75 beam, a shackle rod line, motion transmission means between the shackle rod line and the walking beam, and supporting means operated from said motion transmission means and engageable with the walking 80 beam to support the same and the parts carried thereby in the event of breakage of the shackle rod line.

5. A pump jack including a walking beam and a shackle rod line comprising means 85 for transmitting motion from the shackle rod line to the walking beam, said means including a truss frame having a vertical member connected to the shackle rod line, a horizontal member connected with the 90 walking beam, means for pivotally mounting the horizontal member of the truss frame including a link, and an adjustable rod controlling the position of the link.

E. R. THOMAS.
